UNITED STATES PATENT OFFICE.

JOSEPH B. FOSTER, OF ROANOKE, VIRGINIA.

ATTACHING MEANS FOR ARTIFICIAL TEETH.

1,394,299.

Specification of Letters Patent.

Patented Oct. 18, 1921.

Application filed August 23, 1920. Serial No. 405,449.

To all whom it may concern:

Be it known that I, JOSEPH B. FOSTER, a citizen of the United States, residing at Roanoke, in the county of Roanoke and State of Virginia, have invented new and useful Improvements in Attaching Means for Artificial Teeth, of which the following is a specification.

This invention relates to improvements in means for attaching artificial teeth to natural teeth, and the principal object is to provide improved means for securing a bridge comprising one or more artificial teeth to the adjacent natural teeth.

Another object is to provide such means in which it shall not be necessary to crown the teeth next to the artificial tooth, thus making a much better appearing piece of work.

With these and incidental objects in view, the invention consists of certain novel construction and combination and arrangements of parts, the essential features of which are hereinafter fully set forth and claimed and several forms of which are shown in the accompanying drawings comprising one sheet in which:—

Figure 1 is a view partly in section of one manner of carrying my invention into effect when a single tooth is to be inserted.

Fig. 2 a view similar to Fig. 1 but illustrating the application of the invention to a bridge comprising a plurality of teeth.

Like characters of reference refer to like parts in all views.

This invention contemplates the cheapening of the process of inserting dental bridges; and the provision of a more slightly appearance in such a device. In the present practice, the natural teeth adjacent to the bridge are crowned and to these crowns is attached or anchored the bridge. It is the purpose of the present invention to secure the bridge to the natural teeth by anchor-pins without the necessity of crowning, thus avoiding a costly process and unsightly result.

Referring more particularly to the draw-

ing 1 represents the natural teeth and 2 represents the artificial tooth or teeth.

In Fig. 1, the artificial tooth is provided with anchor pins 6, the wings 7 of which are expanded into apertures drilled in the adjacent teeth and are then cemented in place.

In Fig. 2, is shown the same construction as in Fig. 1 but the bridge comprises a plurality of teeth.

While I have described what are deemed to be the most desirable forms of my invention, it is obvious that the details may be varied without in any way departing from the spirit of the invention and I therefore do not limit myself to the exact details of construction herein set forth nor to anything less than the whole of my invention limited only by the appended claims.

What I claim as new is:—

1. A device of the class described comprising an artificial tooth portion and anchoring means secured in said artificial tooth portion and extending laterally through the side thereof at an acute angle to the vertical axis of said tooth portion, as and for the purpose set forth.

2. A device of the class described comprising an artificial tooth portion and a wire having one end cemented into said artificial tooth portion and its opposite end extended through the side of the tooth portion at an angle to the vertical axis of said tooth portion for seating it in a cavity in a natural tooth, as and for the purpose set forth.

3. A device of the class described comprising an artificial tooth portion and a wire having one end bent in U-formation and secured in said artificial tooth and having its other end extended through and beyond the lateral edge of the artificial tooth for anchoring the same to a natural tooth.

In testimony whereof I have affixed my signature.

JOSEPH B. FOSTER.
